HIGH-VOLTAGE CIRCUIT INTERRUPTER

Ralph H. Earle, Wauwatosa, and Roald H. Amundson, Milwaukee, Wis., assignors to Line Material Company, South Milwaukee, Wis., a corporation of Delaware

Application January 29, 1944, Serial No. 520,180

11 Claims. (Cl. 200—120)

1

This invention relates to high voltage circuit interrupters.

Objects of this invention are to provide an interrupter which is capable of interrupting high voltage, heavy duty circuits and which rapidly extinguishes the resulting arc in an effective and reliable manner.

Further objects are to provide a high voltage, heavy duty, drop-out circuit interrupter in which means are employed, such as a tube for instance, which provides an arc channel with a fusible link located in the arc channel, and to provide means for extending the arc incident to rupture of the fuse link on overload and for drawing the arc into proximity to material adapted to evolve or liberate gas when acted upon by an arc to thereby produce a blast of gas axially of the arc channel to extinguish the arc, the construction being such that after the circuit has been interrupted within the arc channel the device drops out of circuit to an inoperative position.

Further objects are to provide a circuit interrupter which is so constructed that it will effectively interrupt the circuit for a relatively small overload or for a relatively large overload or for any intermediate value of overload with equal certainty of operation in each case, and which is so made that the building up of excessive pressure in the arc channel is prevented.

In greater detail, further objects of this invention are to provide a high voltage, heavy duty fuse construction in which an expellable apertured plug is provided through which a blast of gas is projected to extinguish the arc upon rupture of the fuse link on moderate overloads with the plug so arranged that it is expelled on heavy overloads to provide a larger discharge passageway for the gas to thereby prevent the building up of excessive pressure in the device.

For one form that the invention may take, further objects are to provide a fuse construction in which means are provided for liberating arc extinguishing gas in one portion of the fuse tube to provide a violent blast of arc extinguishing gas which passes outwardly from the adjacent end of the fuse tube and to provide for the normal action of an expulsion fuse construction for the other portion of the device, and in addition to the dual action hereinabove set forth, to provide for the quick mechanical withdrawal of any remaining portion of the fuse link from the fuse tube.

For another form that the invention may take, further objects are to provide a fuse construc-

tion in which a blast of gas is employed for extinguishing the arc, in which plunger or other means withdrawn inwardly of a fuse tube by spring means is employed for leading the arc into proximity to material adapted to evolve gas when acted upon by an arc, means being provided for definitely limiting the travel of the plunger or other means to a predetermined length of path, the construction being such that the spring means is housed within a tube and is protected from the arc and from any gas incident to the arc.

In certain forms that the invention may take, further objects are to provide a fuse construction in which not only an apertured expellable plug is provided which may be expelled under high pressure internally of the device resulting from very heavy overloads, but in which in addition to this though the adjacent end of the fuse tube is closed by a cap, such cap is weakened along a predetermined zone so that a portion of the cap is freely blown from the remainder of the device to provide free venting means, the portion so blown from the device providing an aperture large enough to permit the passage therethrough of the expellable plug.

For several forms of the invention, further objects are to so construct the interrupter that renewal or refill units carrying material adapted to evolve gas when acted upon by an arc may be substituted for the used units so that the major portion of the interrupter may be used over and over again.

Embodiments of the invention are shown in the accompanying drawings, in which:

Figure 1 is a side elevation showing one form of the apparatus, such view showing the interrupter in circuit closed or operative position.

Figure 2 is an enlarged view of the fuse tube removed from the remainder of the apparatus, such view being partly in section and partly broken away.

Figures 3, 4 and 5 are fragmentary sectional views showing further forms of refill devices.

Figure 6 is a fragmentary view showing a further form of the invention.

Figure 7 is a view taken at right angles to Figure 6 and partly in section.

Figure 8 is a view of a fuse tube, partly broken away and partly in section, showing a further form of the invention.

Figure 9 is a view from the lower side of the member to which the lower end of the retracting spring of Figure 8 is attached.

Figure 10 is a view, partly in section, showing another manner in which the arc extinguishing material may be furnished.

Referring to Figure 1, it will be seen that the device comprises upper and lower stationary terminals indicated generally by the reference characters 1 and 2 which are carried by suitable insulators 3 and 4, respectively, which in turn are supported from a suitable supporting member 5. A fuse tube 6 is pivotally supported from the lower terminal 2 and is provided with an upper terminal 7 having outwardly projecting members or pins 8 on opposite sides thereof. The upper stationary terminal 1 may be constructed as set forth in detail in the patent to William O. Schultz No. 2,357,772 of September 5, 1944, for Cut-out construction, and may comprise a pair of spring arms 9 which are pivotally supported by a stationary member 10 and bear against oppositely disposed, downwardly slanting cam portions 11 forming a portion of the stationary member 10. The spring arms are provided with downwardly depressed portions 12 and with outwardly and upwardly slanting guiding portions 13. Normally the projections 8 of the terminal 7 of the fuse tube are hooked behind the downwardly depressed portions 12 of the spring arms 9. The lower stationary terminal 2 may be formed in the manner of a housing as indicated and may be provided with a pair of hook like supporting portions 14. The lower stationary terminal also includes a relatively heavy contact spring 15.

A fuse link is provided within the fuse tube 6 and the flexible leader 16 thereof extends outwardly through the lower open end of the fuse tube, as shown most clearly in Figure 2.

The lower portion of the fuse tube 6 has rigidly clamped thereto a sleeve like member 17 which is provided with a rearwardly and downwardly projecting arm 18 pivoted as indicated at 19 between a pair of arms formed integrally with the main supporting lever 20. This main supporting lever 20 is provided with a pair of trunnions 21 removably supported by the hook like portions 14 of the lower stationary terminal 2 and is provided with a rearwardly projecting portion 22 which normally engages the contact spring 15.

The main lever 20 carries a quick acting flip-out or fuse link extracting lever 23 which is pivotally mounted on a pin 24 carried by the main lever. The main lever has an outwardly extending portion 25. A fuse link clamping lever indicated by the reference character 26 is also pivoted on the pin 24. A spring 27 urges the flip-out lever or fuse link extracting lever 23 and the fuse link clamping lever 26 in opposite directions. The flexible leader 16 is positioned in a grooved portion of the quick acting fuse link extractor or flip-out lever 23 and passes around the outer end thereof and is clamped between the fuse link clamping lever 26 and the extension 28.

When the fuse link is ruptured, as will be described in greater detail hereinafter, the quick acting flip-out lever 23 extracts any remaining portion of the fuse link in a quick manner and rocks in a counterclockwise direction under the influence of the spring 27. The flip-out lever 23 and the fuse link clamping lever 26 are so constructed that they have interengaging portions which come into engagement when the flip-out lever has rocked a predetermined distance so that thereafter the fuse link clamping lever 26 and the flip-out lever 23 rock as a unit and release the leader 16 of the fuse link.

The particular construction of flip-out lever

and fuse link clamping lever forms the subject matter of the United States patent of William O. Schultz Number 2,378,109 of June 12, 1945, for Fuse constructions.

It is apparent that when the fuse link is ruptured, the main lever 20 is no longer held in the position shown in Figures 1 and 2 and it rocks downwardly pivoting about the trunnions 21. This moves the lower end of the fuse tube downwardly and outwardly and allows the projecting portions 8 of the upper contact 7 of the fuse tube to disengage themselves from the latching spring arms 9, such spring arms, however, following the fuse tube downwardly for a predetermined distance and being arrested in their downward motion by means of projections 28 at the lower end of the cam portion 11 of the stationary part of the stationary contact 1. The fuse tube is now free to rock outwardly and downwardly to inoperative position.

The fuse tube is provided with a channel therethrough indicated by the reference character 29 and this channel has an enlarged portion 30. Within this enlarged portion a fiber sleeve 31 is positioned. The fiber sleeve is carried by an outer metal sleeve 32 which has a portion 33 spun into a groove surrounding the fiber sleeve 31. The outer metal sleeve 32 is provided with a flange 34 which rests upon the upper edge of the upper terminal 7 of the fuse tube 6. A Bakelite cap 35 is screwed onto the upper terminal 7 of the fuse tube and has an annular groove 36 formed therein to provide a central portion 37 which is adapted to be blown outwardly upon rupture of the fuse link. The fuse link includes the flexible leader 16 hereinbefore mentioned and a rod like retractable member 38 which is secured to the leader 16 at its lower end and at its upper end is secured to the fusible section 39 and strain wire 40 of the fuse link. The upper end of the fusible section and strain wire are secured to a rivet or button like member 41 which in turn is secured to a metal inverted cup like member 42. The cup like metal member 42 is provided with a plurality of resilient fingers 43 separated by slits as indicated in Figure 2 and these fingers 43 slidably fit within the upper portion of the metal sleeve 32. Gas liberating or evolving material such as the liquid 44 is carried within an annular rupturable container 45 which may, if desired, be made of glass. This container is hermetically sealed and has approximately an elongated torus shape. The retractable rod 38 freely passes through the central opening. The lower end of the container 45 is supported from a plug 46 screwed into the lower end of the fiber sleeve 31 being preferably separated therefrom by means of a small cork washer 47. The upper end of the fiber sleeve 31 has screwed therewith a fiber sleeve 48 and a cork washer 49 is interposed between the sleeve 48 and the container 45. An expellable plug 50 formed of fiber is carried within the aperture in the sleeve 48. It is to be noted that the plug 50 is apertured and loosely receives the upper end 55 of the plunger 38. It is reduced throughout its major portion in external diameter so that it has only a light frictional fit within the aperture of the sleeve 48 and is adapted to be blown therefrom under heavy overloads in a manner herein-
after to be explained.

The operation of the apparatus is as follows: Assume that an overload occurs of moderate value. The fuse link is ruptured at the fusible section and the rod 38 is suddenly drawn downwardly due to the quick acting flip-out or fuse ex-

tracting lever 23. This draws the arc downwardly into proximity to the gas evolving material and ruptures the container 45. The material evolves a quantity of arc extinguishing gas which is projected upwardly through the expellable plug 59. The central portion 37 of the cap is blown off together with the inverted cup-shaped metal member 42 and the violent outward blast of gas acts to extinguish the arc. In addition to this, it will be seen that as the rod or plunger 46 is drawn downwardly if the arc should persist and extend into the arc channel 29, not only the extinguishing action of the blast of gases from the material 44 is provided but in addition to that the normal expulsion action of the device occurs within the portion 29 of the arc channel and therefore there is this dual action that can take place in the event the arc follows the plunger into the portion 29 of the arc channel.

It is to be noted that when the fuse link extracting lever 23 quickly moves down under the influence of the spring 27, a portion thereof finally engages the clamping lever 26 and rocks such clamping lever downwardly as a unit with the flip-out lever, thus freeing the leader 16 and allowing any remaining portion of the fuse link not only to be withdrawn from the tube 6 but to be thrown therefrom. When the fuse link has ruptured, the main lever 20 is released and the fuse tube executes drop-out motion as hereinbefore described.

If a very heavy overload occurs, considerable pressure will build up beneath the expellable plug 59 and such plug will blow outwardly, thereby providing a larger bore through which the blast of arc extinguishing gas may pass thus preventing the building up of excessive pressure within the arc channel. Otherwise the action is the same as that described hereinabove for moderately heavy overloads.

In refusing, the fuse tube is removed from the hook like supporting members 14, see Figure 1, and is refused by unscrewing the remaining portion of the cap 35 and removing the fiber sleeve 31 and the metal sleeve 32. Thereafter a refill unit is positioned. The refill units comprise the sleeve 31 and all of the associated parts including the metal sleeve 32 and the cap 42 as well as a new container 45 and composite fuse link. This refill unit is readily positioned and the leader passed through the fuse tube 6 and secured in place between the clamping lever 26 and the projecting portion 25. Thereafter a new Bakelite cap 35 is screwed into place. The fuse tube 6 is then positioned with its trunnions 21 supported by the hook like members 14 and is rocked upwardly into position. It is to be noted that an eyeleted manipulating portion 51 is provided which is integral with the upper terminal 7 and such portion may be engaged by the switch stick 60 when it is desired to rock the fuse tube back into place.

The material adapted to evolve gas when acted upon by the arc as indicated by the reference character 44 may be any suitable liquid such as carbon tetrachloride, methylene chloride or chloroform, or any other suitable material. As will appear as the description proceeds other material can be employed.

The refill unit may take other forms from that shown in Figure 2. For instance as shown in Figure 3, the refill unit may have the retractable plunger 52 extend only approximately through the container 53. In this case the fusible section and the strain wire indicated respectively at 54 75

and 55 extend through the expellable plug 56. Otherwise the construction is the same as that previously described. In the structure shown in Figure 2 the arc is formed above the plug 50 and is drawn downwardly through the plug into proximity to the arc evolving material. In Figure 3 the arc is formed within the plug 56 and is drawn downwardly into proximity to the arc evolving material.

10 The arc evolving material may be in the form of compressed apertured disks indicated at 57 in Figure 4 and these disks may be carried within a fiber sleeve 58 whose lower end is closed by means of an apertured, screw threaded plug 59.

15 The retractable rod 60 extends through all of the disks 57 of the gas evolving material and at its upper end passes through the expellable plug 61, such plug being frictionally held within the fiber sleeve 62, which latter is screwed into the fiber sleeve 58.

20 The strain wire 63 and the fusible section 64 may extend laterally and upwardly from the upper end of the retractable rod 60 and are attached at their outer ends to the outer metal sleeve 65.

25 The disks 57 may consist of compressed boric acid or other suitable material.

It is also clear that the arc evolving material could be in the form of a powdered material as indicated by the reference character 66 in Figure

30 10. In this case the powdered material is carried within a waxed paper container 67 which has annular fiber ends 68. Silicic acid, gunpowder or other suitable powdered material could be used. In the event the container shown in Figure 10

35 is used, it merely replaces the container 45 of Figure 2, the length and size of the container of course being properly proportioned.

Figure 5 shows a further form of refill device. In this form of refill device the container 69 may

40 be a simple form of glass bottle which contains the liquid 70 of the type hereinbefore described. It is carried within the enlarged upper bore 71 of a fiber sleeve 72. The upper end of the fiber sleeve receives the apertured and threaded plug

45 73. The outer metal sleeve is indicated by the reference character 74. It is to be noted that the sleeve 72 has a constricted opening 75 immediately below the enlarged upper opening 71 and that this constricted opening joins a larger opening 76 by means of a downwardly flaring opening 77. The flexible leader is indicated by the reference character 78 and it is joined by means of the fusible section 79 and strain wire 80 to a conducting strip 81 which is positioned to the side of the

50 container 69 and is electrically connected at its upper end to the metal sleeve 74. With this type of construction the discharge of gas is downwardly through the constricted opening 75 through the expanding portion 77 to the enlarged opening 76 and downwardly through the remainder of the arc channel. When this type of

55 refill device is employed, a permanently closed cap such as shown in the upper end of Figure 8 is employed and the cap is not adapted to be ruptured and expelled upwardly but is to remain intact during the operation of the device as it is desired to have the gas discharge wholly in a downward direction when this type of refill device is employed. The bottle or container 69 em-

60 ployed in Figure 5 is a simple round type of bottle. In the event a flat type of bottle or container is employed as indicated by the reference character 82 in Figures 6 and 7, such bottle is adapted to seat on the lower shouldered portion 83 of an enlarged opening 84 formed in the upper end of

the tube 85. The remainder of the arc channel is smaller as indicated at 86. In this form of the invention two conducting strips indicated at 87 are employed and are positioned on each side of the flat bottle 82. They are carried by a fitting 88 which receives the screw threaded member 89 attached to the upper end of the flexible leader 90. The upper ends of the conducting strips 87 are joined to the upper terminal 91 of the fuse tube 85 by means of a strain wire 92 which has two branch portions at its lower end attached to the strips 87 and which has two branch portions at its upper end attached to the terminal 91. A fusible section 93 also joins at least one of the strips 87 as shown in Figure 7 with the upper terminal 91. In this form of the invention the cap 94 screwed onto the upper terminal 91 is provided with a weakened portion 95 and is adapted to have its central portion 96 blown outwardly therefrom. Also in this form of the invention a shouldered fiber sleeve 97 is positioned in the upper end of the opening 84 of the fuse tube and is held in place on the terminal 91. The expellable fiber plug is indicated at 98.

In this form of device there are no refill units furnished for installation in the field. Instead an entire new fuse tube is furnished. This form of the invention shown in Figures 6 and 7 is primarily intended to show a manner of using a flat type of bottle or container within which the liquid 99 adapted to evolve gas when acted upon by the arc is carried. In this form of the invention the blast of arc extinguishing gas is upwardly through the apertured expellable plug 98, the central portion 96 of the Bakelite cap having been blown outwardly upon rupture of the fuse link. There is also a downward blast of gas which passes downwardly through the restricted channel 86.

In the form of the invention shown in Figure 8 the fuse tube is indicated by the reference character 100. It is provided with an upper terminal 101 which receives the screw threaded metal cap 102. The upper terminal is provided with outwardly projecting members 103 corresponding to the members 8 of Figure 1.

The fuse tube has a uniform bore 104 throughout its major portion. The lower portion of the bore, however, is enlarged as indicated at 105 and terminates in a shoulder 106. Within the enlarged portion 105 of the bore a fiber tube 107 is positioned. This fiber tube is rigidly carried by means of a metal sleeve 108 which has a portion spun into interlocking engagement with the fiber sleeve. The metal sleeve 108 is provided with a flange 109 which is seated against the lower end of the tube 100. It is held in place by means of a threaded metal nut 110. Within the lower end of the metal sleeve 108 a metal cap 111 is slidably positioned. It is preferably provided with a plurality of resilient fingers 112 separated by slots. It is connected by means of a flexible leader 113 with a fuse link extracting lever 114, the leader 113 being held in place by means of a thumb nut 115. The lever 114 is provided with a rounded lower portion 116 beneath which the leader 113 passes.

The lever 114 has a pair of rearwardly projecting arms which are provided with trunnions 117 adapted to seat within the hook like supports 14 of Figure 1. It has a rearwardly projecting portion 118 adapted to engage the lower contact spring 15 of Figure 1. The lower end of the fuse tube is rigidly attached to a sleeve like member

119 which is provided with a rearwardly projecting arm 120 pivoted as indicated at 121 to the main lever 114. It is apparent, therefore, that when the fuse link is ruptured, the main lever 114 moves downwardly and moves the lower end of the fuse tube 100 downwardly and outwardly allowing the upper end to detach itself from the spring arms of the upper stationary contact, the fuse tube thereafter executing drop-out motion.

The fiber sleeve 107 carries an elongated, torus-shaped, hermetically sealed container 122 of glass or other suitable material within which material such as a liquid 123 is carried, the material being adapted to evolve gas when acted upon by an arc, the arc rupturing the container 122. The liquid may be carbon tetrachloride, methylene chloride or chloroform, or any other suitable material. The upper end of the tube 107 is closed by means of a screw threaded apertured plug 124. The lower end of the fiber sleeve or tube 107 receives the threaded fiber sleeve 125. Between the container 122 and the sleeve 125 and the plug 124 cork or similar washers are positioned as indicated in Figure 8.

The fiber sleeve 125 carries the expellable plug 126 of fiber which has a reduced portion out of contact with the sleeve 125 and an enlarged portion slidably held within the sleeve so as to allow the plug 126 to be blown from the fiber sleeve under very heavy overloads.

A retractable plunger 127 freely passes through the container 122 and through the plugs 126 and 124. Its lower end is attached to the flexible leader 113 and the metal cap 111 by means of a strain wire 128 and a fusible section 129. The upper end of the retractable metal plunger 127 is threaded and is received within a fitting or head 130. This head is provided with a flange 131 integral or otherwise rigidly secured thereto. The flange approximately fits the larger bore 105 and is adapted to freely slide upwardly in a manner hereinafter to be described upon rupture of the fuse link. It is brought to rest, however, when it engages the shouldered portion 106 and thus forms a means for definitely arresting the upward motion of the plunger 127 so that the lower end of the plunger 127 never passes through the plug 124.

A tension spring 132 has its lower end secured to the head 130 and its upper end secured to the upper head 133. The lower head 130 and the upper head 133 are also electrically connected by means of the flexible leader 134. The upper head 133 is provided with a reduced externally and internally threaded portion 135 and receives the internally screw threaded metal washer 136. The metal washer 136 is rigidly clamped against the upper terminal 101 by means of the metal screw cap 102.

The fiber sleeve 107 together with the container 122 and the associated parts including the metal cap 111 and the flexible leader 113 constitute a refill unit and it is to be noted that the refill unit may be easily attached to the lower head 130 by screwing the upper end of the retractable plunger 127 into the internally threaded lower head 130. In order to keep the plunger 127 from turning with reference to the sleeve 107 during this operation, it is provided with a transverse pin 137 which seats within a slot formed in the upper portion of the plug 124.

When an overload of moderate magnitude occurs, the fusible section 129 and the strain wire 128 are ruptured and the retractable plunger 127 is quickly drawn upwardly by means of the spring

132, thus leading the arc into proximity to the gas evolving material 128 and rupturing the container 122. A violent blast of arc extinguishing gases is generated and blows outwardly through the restricted aperture in the expellable plug 126 and extinguishes the arc. The main lever 114 rocks downwardly and moves the lower end of the fuse tube downwardly and outwardly and allows the fuse tube to drop out of position as hereinbefore described. It is to be noted particularly that the upward stroke of the retractable plunger is definitely limited by the stop means provided by the flange 131 and the shoulder 106. It is preferable to provide cut-outs 138 in the flange 131 to allow free passage of air and to prevent retardation of the upward motion of the plunger 127.

If a heavy overload had occurred, the operation is the same as hereinabove described except for the fact that the expellable plug 126 is blown out from the lower end of the tube 125 and a larger aperture is provided for the discharge of gases. This prevents the building up of excessive pressure within the device even under very heavy overloads.

It is to be understood that in all forms of the invention the cork washers on opposite sides of the container are merely cushioning washers and are very thin and are immediately destroyed or blown outwardly during the operation of the apparatus under overload.

The reason for detachably coupling the upper head 133 with the metal washer 136 is to facilitate reloading of the device.

In refusing the device, the operator removes the cap 102 and unscrews the washer 136 from the upper head 133. Thereafter the operator unscrews the old rod 127 from the head 130 and the refill unit is thereafter attached to the lower head 130 by screwing the rod 127 of the new unit into the lower head 130. Thereafter the operator screws the lower end of a threaded rod, not shown, into the internally threaded portion of the reduced part 135 of the upper head 133 and passes this rod upwardly through the fuse tube and passes the rod through the metal washer 136. He then draws the rod upwardly and as soon as the flange 109 of the refill unit is seated against the lower end of the fuse tube 100, he continues drawing the rod upwardly and thus extends the spring 132. When he has drawn the upper portion 135 of the upper head 133 slightly above the upper end of the fuse tube, he screws the metal washer 136 onto the reduced portion 135 and allows the washer 136 to come to rest against the upper terminal 101 of the fuse tube. Thereafter he replaces the threaded cap 102 at the upper end of the fuse tube and the nut 110 at the lower end of the fuse tube. He then attaches the flexible leader to the lever 114 by means of the thumb nut 115 and the device is then ready to be repositioned and rocked back into operative position.

It is to be noted that in all forms of the invention the drop-out fuse tube is adapted to be removed and repositioned by means of a switch stick and after being repositioned is rocked into operative position by means of the switch stick.

In all forms of the invention it is apparent that the fuse tube may be made of fiber or may be made of Bakelite lined with fiber in a well known manner.

It will be seen that this invention provides novel forms of high voltage, heavy duty circuit interrupters in which provision is made for caring for both heavy and light overloads and for

overloads of all intermediate values. Under a light overload a relatively restricted passage is provided for the blast of arc extinguishing gas, whereas for a relatively heavy overload the expellable plug is expelled and a larger passage is provided for the blast of arc extinguishing gases. In this manner excessive building up of pressure internally of the device is prevented.

10 While a few of the possible arc extinguishing materials have been illustrated, it is to be understood that any suitable type of arc extinguishing material may be used provided the material liberates or evolves gas when acted upon by an arc.

15 It is to be noted that the fuse link is a composite structure and in the form shown consists of the fusible section, the strain wire, the retractable plunger and the flexible leader.

20 In all forms of the invention it is to be noted that the fuse tube has an arc channel therethrough which is divided into two portions, in one of which the blast of arc extinguishing gas is produced. The other portion of the arc channel provides a part into which a portion of the fuse link is retracted in all forms of the invention and, 25 in the form shown in Figures 2 and 6, this other portion provides a fuse link expulsion portion which has a true expulsion action.

It is to be noted also that in all forms of the invention except that shown in Figures 6 and 30 7 the major portion of the device is used over and over and refill units are supplied the user so that he may install the refill units without returning the tube to the factory. On the other hand, in the form of the invention shown in 35 Figures 6 and 7 it would be the practice to return the entire tube to the factory and the customer would then be furnished with a new refilled tube. The old tube would be used over and over again but it would be refused at the 40 factory as distinguished from the other forms of the invention.

It is to be noted that the fusible section of the fuse link is kept in spaced relation to the gas liberating material. It is to be noted that the fuse link heats up to a considerable degree when it is carrying somewhat near its full rated load. By having the fusible section spaced from the gas liberating means, there is less chance of rupturing the container carrying the gas liberating means than if the fusible section of the fuse link was in contact with or immediately adjacent the container of the gas liberating means.

It is to be noted that the cap of the refill units, such as shown in Figures 2 and 3, forms an arc 55 chamber in addition to the two-part arc channel hereinabove described.

Although this invention has been described in considerable detail, it is to be understood that such description is intended as illustrative rather than limiting, as the invention may be variously embodied and is to be interpreted as claimed.

We claim:

1. A circuit interrupter comprising a body portion provided with an arc channel, interrupting means adapted to interrupt a circuit under overload and form an arc in said arc channel, gas liberating means adapted to liberate a gas when acted upon by an arc, said gas liberating means being spaced axially of said body portion from said interrupting means, said body portion being tubular and having a portion extending beyond said gas liberating means in a direction away from said interrupting means and having a permanently open end, and an expellable apertured plug through which said arc is formed and

through which the liberated gas passes to extinguish said arc, said plug being normally positioned and retained in said arc channel solely by friction, said plug remaining in place in said arc channel for moderate overloads to provide a restricted passage and being expelled on heavy overloads to provide a larger passage.

2. A circuit interrupter comprising a body portion provided with an arc channel, interrupting means adapted to interrupt a circuit under overload and form an arc in said arc channel, gas liberating means adapted to liberate a gas when acted upon by an arc, said gas liberating means being spaced axially of said body portion from said interrupting means, said body portion being tubular and having a portion extending beyond said gas liberating means in a direction away from said interrupting means and having a permanently open end, said gas liberating means being located within said arc channel, and an expellable apertured plug through which said arc is formed and through which the liberated gas passes to extinguish said arc, said plug being normally positioned and retained in said arc channel solely by friction, said plug remaining in place in said arc channel for moderate overloads to provide a restricted passage and being expelled on heavy overloads to provide a larger passage.

3. A circuit interrupter comprising a body portion provided with an arc channel, interrupting means adapted to interrupt a circuit under overload and form an arc in said arc channel, gas liberating means adapted to liberate a gas when acted upon by an arc, said gas liberating means being spaced axially of said body portion from said interrupting means, said body portion being tubular and having a portion extending beyond said gas liberating means in a direction away from said interrupting means and having a permanently open end, means for leading an arc into proximity to said gas liberating means, and an expellable apertured plug through which said arc is formed and through which the liberated gas passes to extinguish said arc, said plug being normally positioned and retained in said arc channel solely by friction, said plug remaining in place in said arc channel for moderate overloads to provide a restricted passage and being expelled on heavy overloads to provide a larger passage.

4. A circuit interrupter comprising a body portion provided with an arc channel, interrupting means adapted to interrupt a circuit under overload and form an arc in said arc channel, gas liberating means adapted to liberate a gas when acted upon by an arc, said gas liberating means being spaced axially of said body portion from said interrupting means, said body portion being tubular and having a portion extending beyond said gas liberating means in a direction away from said interrupting means and having a permanently open end, a retractable plunger for leading an arc into proximity to said gas liberating means, and an expellable apertured plug through which said arc is formed and through which the liberated gas passes to extinguish said arc, said plug being normally positioned and retained in said arc channel solely by friction, said plug remaining in place in said arc channel for moderate overloads to provide a restricted passage and being expelled on heavy overloads to provide a larger passage.

5. A circuit interrupter comprising a body portion provided with an arc channel, means

dividing said arc channel into a first and a second portion, a fuse link in said arc channel having a fusible section located in the first portion of said arc channel and extending through the second portion of said arc channel, gas liberating means located in the first portion of said arc channel adapted to liberate gas when acted upon by the arc incident to the blowing of said fuse link, and means tending to draw said fuse link outwardly from the second portion of said arc channel, the second portion of said arc channel having an expulsive action in the event the arc is not extinguished by the gas liberated in the first portion of said arc channel.

15 6. A circuit interrupter comprising a body portion provided with an arc channel, means dividing said arc channel into a first and a second portion, a fuse link in said arc channel having a fusible section located in the first portion of said arc channel and extending through the second portion of said arc channel, gas liberating means adapted to liberate gas when acted upon by an arc, said gas liberating means being spaced axially of said body portion from the fusible section of said fuse link, and means tending to draw said fuse link outwardly from the second portion of said arc channel, the second portion of said arc channel having an expulsive action in the event the arc is not extinguished by the gas liberated in the first portion of said arc channel.

30 7. A circuit interrupter comprising a body portion provided with an arc channel, means dividing said arc channel into a first and a second portion, a fuse link in said arc channel having a fusible section located in the first portion of said arc channel and extending through the second portion of said arc channel, gas liberating means adapted to liberate gas when acted upon by an arc, said gas liberating means being spaced axially of said body portion from the fusible section of said fuse link, biased plunger means for drawing the arc incident to rupture of said fuse link into proximity to said gas liberating means, and means tending to draw said fuse link outwardly from the second portion of said arc channel, the second portion of said arc channel having an expulsive action in the event the arc is not extinguished by the gas liberated in the first portion of said arc channel.

45 8. A circuit interrupter comprising a body portion provided with an arc channel, gas liberating means within said arc channel adjacent one end of said arc channel, said gas liberating means adapted to liberate gas when acted upon by an arc, a cap normally closing the end of said arc channel and having a weakened portion adapted to be ruptured by gas pressure to permit the central portion of said cap to be blown off, and an expellable apertured plug located in said arc channel and normally restricting said arc channel for moderate overloads and adapted to be blown from said arc channel through the opening in said cap resulting from the blowing off of the central portion of said cap, the blowing of said plug from said arc channel occurring on heavy overloads.

60 9. A circuit interrupter comprising a body portion provided with a channel; a renewable refill unit adapted to be positioned in said channel and comprising a sleeve, a retractable conductor, a fuse link including a fusible section connected to said conductor, an expellable apertured plug carried by said sleeve and adapted to be blown therefrom on heavy overloads, and gas liberating means 65 in said sleeve spaced axially of said refill unit

from said fusible section and adapted to liberate gas when acted upon by the arc incident to blowing of the fuse; and retracting means detachably connected to said conductor.

10. A circuit interrupter comprising a body portion provided with a channel extending through the body portion; a renewable refill unit adapted to be positioned in said channel and comprising a sleeve, a fuse link including a fusible section and a retractable conductor, an expellable apertured plug carried by said sleeve and adapted to be blown therefrom on heavy overloads, and gas liberating means in said sleeve adapted to liberate gas when acted upon by the arc incident to blowing of the fuse; and retracting means located externally of the channel of said body portion for moving said conductor to elongate the arc.

11. A renewable refill unit for a circuit interrupter, said unit comprising an insulating outer sleeve, a container positioned in one end of the sleeve and defining a bore disposed axially of the sleeve, a fiber sleeve positioned in the other end of said outer sleeve and defining a bore coaxial

with the first mentioned bore, closure means at said other end defining an arcing chamber exteriorly of said bores, a conductive rod extending through said bores to said chamber, and a fuse section in said chamber electrically connected to said rod, said rod being movable out of said bores on rupture of said fuse section.
